(57) **CLAIM**

The ornamental design for a tooth for cutting edge, as shown and described.

DESCRIPTION

FIG. 1 is a top front perspective view of the tooth for cutting edge showing my new design;

FIG. 2 is a front perspective view thereof;

FIG. 3 is a bottom rear perspective view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a cross-sectional view from FIG. 4 taken along section lines 8-8.

The evenly spaced broken lines are included to show portions of the tooth for cutting edge that form no part of the claimed design. The long and short broken lines that define the bounds of the claimed design form no part thereof.
